(57) **CLAIM**

The ornamental design for a game console, as shown and described.

DESCRIPTION

FIG. 1 is a front, right, bottom perspective view of the first embodiment of a game console, showing my new design; FIG. 2 is a rear, left, top perspective view thereof;

FIG. 3 is a front elevational view of the enlarged scale thereof;

FIG. 4 is a rear elevational view of the enlarged scale thereof;

FIG. 5 is a left side view of the enlarged scale thereof;

FIG. 6 is a right side view of the enlarged scale thereof;

FIG. 7 is a top plan view of the enlarged scale thereof;

FIG. 8 is a bottom plan view of the enlarged scale thereof;

FIG. 9 is an enlarged view of detail 9 in FIG. 1;

FIG. 10 is an enlarged view of detail 10 in FIG. 1;

FIG. 11 is an enlarged view of detail 11 in FIG. 2;

FIG. 12 is an enlarged view of detail 12 in FIG. 3;

FIG. 13 is an enlarged view of detail 13 in FIG. 5;

FIG. 14 is an enlarged view of detail 14 in FIG. 5;

FIG. 15 is an enlarged view of detail 15 in FIG. 6;

FIG. 16 is an enlarged view of detail 16 in FIG. 7;

FIG. 17 is a front, right, bottom perspective view of the second embodiment of a game console, showing my new design;

FIG. 18 is a rear, left, top perspective view thereof;

FIG. 19 is a front elevational view of the enlarged scale thereof;

FIG. 20 is a rear elevational view of the enlarged scale thereof;

FIG. 21 is a left side view of the enlarged scale thereof;

FIG. 22 is a right side view of the enlarged scale thereof;

FIG. 23 is a top plan view of the enlarged scale thereof;

FIG. 24 is a bottom plan view of the enlarged scale thereof;

FIG. 25 is an enlarged view of detail 25 in FIG. 17;

FIG. 26 is an enlarged view of detail 26 in FIG. 17;

FIG. 27 is an enlarged view of detail 27 in FIG. 18;

FIG. 28 is an enlarged view of detail 28 in FIG. 19;

FIG. 29 is an enlarged view of detail 29 in FIG. 21;

FIG. 30 is an enlarged view of detail 30 in FIG. 21;

FIG. 31 is an enlarged view of detail 31 in FIG. 22; and,

FIG. 32 is an enlarged view of detail 32 in FIG. 23.

The short dash-dot lines depict portions of the game console that form no part of the claim.

The dash-dot lines illustrate bound of the magnified portions and form no part of the claim.

1 Claim, 32 Drawing Sheets
